UNITED STATES PATENT OFFICE.

HARRY JOSEPH NULLETT, OF MEMPHIS, TENNESSEE.

SALT-VAPOR CABINET.

1,375,602.

Specification of Letters Patent. Patented Apr. 19, 1921.

Application filed April 2, 1920. Serial No. 370,730.

To all whom it may concern:

Be it known that I, HARRY JOSEPH NULLETT, a citizen of the United States, residing at Memphis, in the county of Shelby and State of Tennessee, have invented new and useful Improvements in Salt-Vapor Cabinets, of which the following is a specification.

This invention has reference to a medicinal vapor cabinet.

An object is to produce a cabinet in which a vapor is directed therein through a medicament, such as a salinous body, so that the healing and soothing property thereof will be directed to and absorbed in the pores of a patient using the cabinet.

A further object of the invention is to produce a medical vapor cabinet in which the walls thereof are divided into compartments, the inner series of which having perforated walls and receiving therein a granulated salinous body of medicinal properties, the outer compartments serving as ducts for a vapor which is generated in the bottom of the cabinet, and the said vapor is directed through the perforated walls of the medicament compartments into the cabinet, carrying therewith the medicinal properties of the medicament and directing the same against the occupant of the cabinet.

A further object is to produce a medical vapor cabinet in which a vapor is caused to travel through a medicinal body and enter the cabinet, the said cabinet having on the interior thereof means for preventing the patient contacting with its walls and also means whereby the patient will be wholly inclosed in the cabinet.

The foregoing objects, and others which will appear as the nature of the invention is better understood, may be accomplished by a construction, combination and operative arrangement of parts, such as is illustrated by the drawings.

45 In the drawings:—

Figure 1 is a vertical longitudinal sectional view through the improved cabinet.

Fig. 2 is a horizontal sectional view approximately on the line 2—2 of Fig. 1.

50 My improved cabinet is broadly indicated by the numeral 10. The cabinet includes a compartment 11 for the patient. For distinction the floor of the compartment 11 is indicated by the numeral 12. The walls 55 of the compartment 11, at a considerable distance below the upper edges thereof are

perforated, as at 13 and form the inner walls of medicament compartments 14. By reference to the drawings it will be seen that the front of the occupant compartment 60 11 is open, but the same is designed to be closed by a hinged door 15, suitable latching means 16 being provided for retaining the door closed. It will also be noted that all of the walls of the cabinet extend a suitable distance below the floor 12, and the floor 12 is preferably supported on brackets 65 17 that are secured to the outer walls 18 of the vapor compartments 19 and to the front wall 20 of the device. The floor 12 may 70 also serve as the bottom wall of the compartments 11 and 19. Below the floor 12, and preferably supported by brackets 21 is a sub-floor 22. This floor, being elevated a suitable distance above the lower edge 75 23 of the cabinet, is preferably perforated, as indicated by the numeral 23. The floors 12 and 22 provide a compartment 24 for a heater 25, and above the heater is supported a water receptacle 26. 80

The floor 12, at the portion thereof directly below the vapor compartments 19 is perforated, as indicated by the numeral 27, whereby the vapor from the heated water in the receptacle 26 may be directed through 85 said compartments. The dividing walls 28 between the medicament compartment 14 and the vapor compartment 19, are perforated, as indicated by the numeral 29.

The heater compartment has an opening 90 which is closed by a door 30. The door is preferably, but not necessarily, slidably, and through the opening therefor the heater may be regulated and the water receptacle 26 replenished or removed. The vapor compartments 19 have their outer or upper portions sealed, as indicated by the numeral 31, but the medicament compartments 14 are open at the top thereof. The open tops, however, are normally closed by hinged 95 doors 32 that are provided with latching or locking means 33. The medicament compartments, at the lower portions thereof are also preferably provided with openings that are closed by doors 34 whereby the medicament in the said compartments may be removed, the medicaments being arranged in the compartments through the openings closed by the doors 32. 100

The walls of the occupant compartment 11, as previously inferred, project a suitable distance above the medicament and vapor 110

compartments, and on the side and rear walls of the said compartments 11 there are vertical posts 35. The posts are preferably in the nature of round poles and are also 5 preferably spaced from the walls of the compartment 11. Connected to these posts are spaced curved members 36 which are also preferably round in cross section, and the members 36 provide a rest for the back 10 of the patient occupying the cabinet.

The top of the cabinet is open, but the side walls, at the rear thereof have outwardly extending brackets 37 in which is journaled the trunnion ends of a roller 38. 15 This roller may be and preferably is spring influenced, and has secured thereon a curtain 39. When the patient enters the cabinet the door 15 thereof is closed and the curtain is drawn over the open top of the 20 compartment 11 so that the vaporized medicament cannot escape through either the front or top of the compartment 11. The curtain 39 is provided with a latch 40 that engages with the inner face of the door 15, 25 or any other convenient part of the device for holding the top of the compartment 11 closed.

The medicament employed is preferably of a salinous nature which is pulverized so 30 that the same may be readily inserted in or removed from the medicament compartments. The salinous body fully fills the compartments and constitutes a pervious body for each of such compartments through 35 which the vapor must necessarily pass from the vapor compartments into the occupant compartment, and being absorbed in the pores of the patient will have both a soothing and healing effect.

40 Having thus described the invention, what I claim is:—

1. A vapor cabinet, including an occupant compartment, having an open front and an open top, a door closing the front, 45 a curtain for closing the top, vapor generating means below the compartment, medicament holding compartments disposed

against the sides and back of the occupant compartment and having perforate communications therewith, and vapor compartments positioned against the medicament compartments having perforated communications therewith and with the vapor generating means. 50

2. A vapor cabinet including an occupant compartment having an open front and an open top, a door for closing the front, a curtain for closing the top, vapor generating means below the compartment, medicament holding compartments arranged against the 60 sides and back of the occupant compartment having perforate communications therewith, said medicament holding compartments having open tops, hinged doors for closing the same, said compartments having openings at the bottom thereof, doors for closing said openings, vapor conducting compartments on the outer sides of the medicament holding compartments and having perforated communications with the said medicament compartments and also having perforate communications with the vapor generating means, whereby the vapors will be directed through the vapor compartments 65 through the medicament in the medicament compartments and into the occupant compartment. 70

3. A vapor cabinet including an occupant compartment, medicament containing compartments thereagainst and having 80 perforate communications therewith, a vapor conducting compartment for each of the medicament compartments and having perforate communications with the said medicament compartments, a door for closing 85 the front of the occupant compartment, a curtain for closing the top of the occupant compartment, rods on the sides of the occupant compartment and on the back of the occupant compartment, and curved rods 90 connecting said first mentioned rods, for the purpose set forth.

In testimony whereof I affix my signature.
HARRY JOSEPH NULLETT.
